UNITED STATES PATENT OFFICE

2,309,437

ADJUSTABLE BEARING FOR DOOR
LOCKING BOLTS

Herbert Cady Blodgett, Hartford City, Ind., assignor to Overhead Door Corporation, Hartford City, Ind., a corporation of Indiana

Application July 12, 1941, Serial No. 402,095

5 Claims.

(Cl. 292—1)

This invention relates to improvements in adjustable bearing for door locking bolts.

The main objects of this invention are:

First, to provide an adjustable guide for the bolts or locking rods for vertically slidable doors adapted to conveniently adjust the parts in initial installation and to be adjusted for relative shifting of the door and door frame and the tracks.

Second, to provide a device of this character which is exceedingly simple and permits adjustments to be effective as desired quickly and commonly without the aid of tools.

Objects relating to details and economies of the invention will appear from the description to follow. The invention is defined in the claims.

A preferred embodiment of the invention is illustrated in the accompanying drawing, in which:

Fig. 1 is an inside elevational view of a vertically sliding door equipped with the adjustable bolt guide of my invention.

Fig. 2 is an enlarged fragmentary view partially in horizontal section illustrating the relation of the door, its track, the bolt, and the adjustable guide member for the bolt.

Fig. 3 is a fragmentary front elevation of the guide structure and bolt associated therewith, the guide structure being shown partially broken away and partially in section.

Fig. 4 is an enlarged fragmentary view partially in vertical section on line 4—4 of Fig. 1.

In the accompanying drawing, 1 represents a door casing or frame and 2 a vertically slid-able door made up of sections 3—3 articulated or hinged together at 4. Tracks 5 are provided for the door guiding and supporting rollers 6. These tracks are supported by suitable brackets 7. This association of parts is old in the art.

I provide a door locking means comprising a pair of rod-like bolts 8 pivotally connected at their inner ends to the actuating member 9 which is provided with a handle 10. It will be noted that the bolts are eccentrically pivoted to the actuating member. A key controlled locking means designated generally by the numeral 11 is commonly provided for securing the actuating member 9 in its actuated position.

The tracks are provided with slots 12 adapted to receive the bolts when they are in actuated position.

It is quite common experience for the floor or sill portion against which the door closes to change positions or of some part to settle which shifts the bolts relative to their keepers and

prevents engagement thereof. Commonly, a guide member is provided such as is shown in the Johnson Patent 1,983,856, issued December 11, 1934, this guide member being bolted to the door. To shift the same requires a mechanic or person of skill. I provide means whereby the outer end of the bolt may be quickly and easily adjusted to guide it to its keeper.

This means comprises a casing-like bracket or support 13 which is fixedly secured to the door by the bolts or lag screws 14. This support member is provided with vertical slots 15 in its vertical side walls, these slots being very substantially longer than the width of the bolt.

Within the support member 13 I mount a vertically adjustable bolt guide or bearing member 16, this member being supported by the bolt 17 arranged through the slot 18 in the front wall of the support member, the bolt being provided with a thumb nut 19, so that by loosening this thumb nut the guide member may be quickly adjusted to guide the outer end of the bolt to its keeper and the nut quickly tightened to clamp the guide member in its adjusted position. This may be quickly accomplished without the aid of tools and by persons having little or no mechanical skill which is a very great factor as it is found to avoid many servicing trips otherwise required. It will be appreciated that such servicing trips are quite expensive, and the need of such servicing is of annoyance to all parties concerned inasmuch as the old structure frequently required the removal of the bolts and screw, and in replacing the same it was likely to leave the door more or less marred. My invention eliminates all of these objections. Further, it is of value not merely from the readjustment standpoint but from the initial installation as it provides for adjusting to meet varying conditions and may be adjusted by an unskilled workman or person.

I have illustrated and described my improvements in a very practical commercial embodiment thereof. I have not attempted to illustrate or describe various adaptations that are possible as it is believed that this disclosure will enable those skilled in the art to embody or adapt my invention as may be desired.

Having thus described the invention what is claimed as new and desired to secure by Letters Patent is:

1. In a vertically sliding door structure includ-ing a door and a track therefor, the combina-tion of a rod-like bolt, said track having a slot therein constituting a keeper for said bolt, a

rotatable bolt actuating member to which the inner end of said bolt is eccentrically pivoted, a guide for the outer end of said bolt comprising a support housing mounted on said door adjacent said track and having a vertical slot in the side wall thereof through which said bolt is disposed and a vertical slot in its front wall, and a bearing member arranged within said support housing and adapted to slidably receive and support said bolt internally of said housing, said bearing member being provided with an element disposed through said slot in the front wall of said support housing and provided with a clamping nut engaging said element externally of the housing whereby the bearing member may be vertically adjusted to position the bolt relative to the keeper.

2. In a vertically sliding door structure including a door and a track therefor, the combination of a rod-like bolt, said track having a keeper for said bolt, a bolt actuating member by which the inner end of said bolt is swingably supported, a combined support and guide for the outer end of said bolt comprising a support housing mounted on said door adjacent said track and having a vertical slot substantially longer than the width of the bolt and through which said bolt is disposed and a second vertical slot, and a bearing member adapted to slidably receive and support said bolt internally of said housing, said bearing member being provided with an element disposed through said second slot in said support housing and provided with a clamping nut engaging said element externally of the housing whereby the bearing member may be vertically adjusted to position the bolt relative to said keeper.

3. In a vertically sliding door structure including a door and a track therefor, the combination of a locking bolt, said track being provided with a keeper for said bolt, bolt actuating means operatively associated with the inner end of said bolt, and guide means for the outer end of said bolt comprising a bracket carried by the door, a bearing member slidably receiving

and supporting the outer end of said bolt and mounted on said bracket for vertical adjustment thereon to vertically adjust the path of movement of the bolt supported by said bearing member relative to said bracket, and means for effecting said vertical adjustment comprising a clamping element on said bearing member engaging in a slot in the bracket and a further clamping element engaging said first named element whereby the bearing member may be clamped in its vertically adjusted position on the bracket.

4. In a vertically sliding door structure including a door and a track therefor, the combination of a locking bolt, said track being provided with a keeper for said bolt, bolt actuating means operatively associated with the inner end of said bolt, and guide means for the outer end of said bolt comprising a bracket carried by the door and a bearing member slidably receiving and supporting the outer end of said bolt and mounted on said bracket for vertical adjustment thereon to vertically adjust the path of movement of the bolt supported by said bearing member relative to said bracket, and means for securing said bearing member in its vertically adjusted position on said bracket without the aid of tools.

5. In a vertically sliding door structure including a door and a track therefor, the combination of a locking bolt, said track being provided with a keeper for said bolt, bolt actuating means operatively associated with the inner end of said bolt, a bracket carried by the door, and a bearing member slidably receiving and supporting the outer end of said bolt and mounted on said bracket for vertical adjustment thereon to vertically adjust the path of movement of the bolt supported by said bearing member relative to said bracket, and means for securing said bearing member in its vertically adjusted position on said bracket comprising a clamping bolt and a coacting nut.

HERBERT CADY BLODGETT.
